AQUARIUM HEATER

Harding W. Willinger and Herbert N. Nestler,
New York, N. Y.

Application June 4, 1952, Serial No. 20,020

Term of patent 14 years

(Cl. D81—10)

FIG.1.

FIG.2.

FIG.3.

To all whom it may concern:

Be it known that we, Harding W. Willinger and Herbert N. Nestler, citizens of the United States, residing at New York, N. Y., have invented a new, original, and ornamental Design for an Aquarium Heater, of which the following is a specification, reference being had to the accompanying drawing, forming part thereof.

Figure 1 is a front elevational view of an aquarium heater showing our new design.

Figure 2 is a side elevational view thereof.

Figure 3 is a top view thereof.

We claim:

The ornamental design for an aquarium heater, substantially as shown.
